BAG

John N. Tooker, Canajoharie, N. Y., assignor, by
mesne assignments, to Arkell & Smiths,
Canajoharie, N. Y., a corporation of New York

Application March 11, 1938, Serial No. 195,226

2 Claims. (Cl. 229—55)

The present invention relates to multi-ply paper bags that are particularly adapted for packaging cement and other weighty material, and further relates to a method of making such bags.

5 The object of the invention is to provide a novel and improved bag and method of this character.

The invention is illustrated by way of example in the accompanying drawing, in which:

Figure 1 is a plan view of two paper strips from 10 which the bag tube may be formed;

Fig. 2 is a transverse sectional view of the bag tube;

Fig. 3 is a side view of one end portion of the bag tube when flattened;

15 Fig. 4 is a plan view of the upper portion of a bag tube with a pasted or satchel end partially formed;

Fig. 5 is a corresponding view with the satchel end completed;

20 Figs. 6 and 7 are sectional views on an enlarged scale taken on the lines 6—6 and 7—7 of Fig. 5.

My improved bag as illustrated in the drawing is of the type of the ones described and claimed in Letters Patent to Bartlett Arkell, No. 1,805,067, dated May 12, 1931, and John N. Tooker, No. 1,933,776, dated November 7, 1933.

25 As shown, instead of the bag tube being made of a single strip of paper as in the case of the bag tubes illustrated in said patents, it is made of 30 two or more strips of paper 2 and 4, the strip 2 being preferably narrower than the strip 4.

The strips 2 and 4 may be of equal length and 35 cut from separate supply strips 3 and 5, and the two strips brought together in superposed relation with the forward end 6 of the narrower strip 2 spaced a distance beyond the forward end of the wider strip, and the rear end of the narrower strip spaced a distance forwardly from the rear end of the wider strip. When the strips are brought together the longitudinal edges of the narrower strip 2 are spaced a distance inwardly from the longitudinal edges of the wider strip 4.

40 Previously to positioning the strips together and preferably before the cutting off of the strips, adhesive 8 is applied to one of the strips so that when the two strips are brought together the longitudinal margins and the rear end of the narrower strip are secured to the wider strip and the forward end of the wider strip is secured to the 45 narrower strip.

The two strips are wound upon themselves on a suitable cylindrical mandrel with the narrower strip 2 on the inside and the projecting end 6 of the narrower strip innermost. The strips may 50 be brought together as above described at the

point where the strips start to wind on the mandrel or previously to the winding.

In the bag tube illustrated in the drawing, the two strips are wound slightly more than twice around the mandrel so as to make a four-ply tube, 5 but the number of plies may be varied as desired. By thus winding the composite strip, the outer end 7 (Fig. 2) of the narrower strip extends a distance over the inner end 6 of the narrower strip and the outer end 9 of the wider strip extends a distance over the inner end 11 of the wider strip, thus insuring at least four plies all 10 around the bag tube. The projecting end of the narrower strip 6 is at least the length of one half of a convolution, and the projecting end of the wider strip is also preferably at least the 15 length of one half of a convolution.

Previously to the winding operation adhesive is 20 suitably applied so that the inner end of the narrower strip is adhesively secured to the overlying ply or convolution and the outer end of the narrower strip is adhesively secured to the overlying ply or convolution, and the inner end of the wider strip is adhesively secured to the overlying convolution and the outer end of the wider 25 strip is adhesively secured to the underlying convolution.

When the two strips are thus wound, the resulting tube is flattened preferably on the line A—A shown in Fig. 2 so as to space the secured 30 ends of the strips from the lines of creasing.

When the tube has thus been wound and flattened the ends thereof are preferably closed by forming a pasted or satchel end by means of the usual ending machine.

In Fig. 4 the end of the tube is shown spread and flattened and adhesive applied to the side flaps 10 and end flaps or tucks 12, the adhesive in this figure being shown omitted from one of the 35 end tucks so as to form a valve.

It will be noted that in the case of the side flaps, the convolutions of the wider strip project a distance beyond the convolutions of the narrower strip so as to produce a shingle arrangement 40 whereby, when the two side flaps are brought together, the margins of both the wider and narrower strip of the outer flap are secured to the outer ply of the under flap. It will also be noted by reference to Figs. 6 and 7 that in the case of the end flaps the plies that are made up of the wider 45 strip project a distance inwardly beyond the plies that are made up of the narrower strip. This construction makes a secure end closure and the shingled effect eliminates several layers of paper and the paste necessary to fasten them together, 50 55

thereby making the ends more flexible. Consequently the finished bag when filled with material assumes more readily a rounded shape at the ends, thus obviating the danger of the flaps peeling open from pressure when the filled bags are piled up. The offset or shingling effect at the ends being all around the bag, gives a more flexible end to the inner extremity of the valve flap, thus creating an easier and tighter closing effect of the valve.

10 It will also be apparent that by using two or more strips of paper as described, it is possible to much more quickly wind the tube than is possible with the use of a single strip. This two-strip arrangement also allows the use of strips of paper of different weight bases, thus allowing a heavier sheet on the outside of the finished bag where the strength is most needed.

15 As will be evident to those skilled in the art, my invention permits various modifications without departing from the spirit thereof or the scope of the appended claims.

What I claim is:

1. A multi-ply paper bag tube comprising a composite strip made up of two strips of different widths, the narrower strip having its longitudinal edges spaced inwardly from the adjacent edges of the wider strip and having one end projecting a distance beyond the adjacent end of the wider strip, the composite strip being wound in the direction of its length into a tube with the narrower strip forming the inner ply of the com-

posite strip and said projecting end innermost, at least one end of the tube having a pasted satchel end formed thereon with portions of both strips of one of the side flaps of the satchel end adhesively secured over the underlying side flap, 5 said tube comprising at least two complete convolutions of said composite strip, and said projecting end of the narrower strip being at least the length of one-half of a convolution.

2. A multi-ply paper bag tube comprising a 10 composite strip made up of two strips of different widths, the narrower strip having its longitudinal edges spaced inwardly from the adjacent edges of the wider strip, the narrower strip having one end projecting a distance beyond the adjacent end 15 of the wider strip and the wider strip having its other end projecting a distance beyond the end of the narrower strip, the composite strip being wound in the direction of its length into a tube with the narrower strip forming the inner ply of 20 the composite strip and said projecting end innermost, at least one end of the tube having a pasted satchel end formed thereon with portions of both strips of one of the side flaps of the satchel end adhesively secured over the underlying side 25 flap, said tube comprising at least two complete convolutions of said composite strip, and said projecting end of each strip being at least the length of one-half of a convolution.
